ENGINE FRAME

Arne Feroy, New York, N. Y., assignor to Rogers
Diesel and Aircraft Corporation, New York,
N. Y., a corporation of New York

Application September 4, 1944, Serial No. 552,600

2 Claims. (Cl. 123—173)

This invention relates to engine frames in general, and more specifically to cylinder liner and cylinder block constructions for opposed-piston internal combustion engines. The invention is applicable to all such engines of crosshead construction, i. e. those not using trunk pistons, but it will be described as applied to an engine of the class commonly called barrel type, axial, or round engines, the class having cylinders parallel to the shaft.

An object of the invention is to provide a welded frame structure for an opposed-piston barrel engine, with removable cylinder liners, each having its own water jacket and each received in a bore in the frame, the same bore serving also as crosshead guides for the crossheads of a pair of opposed-piston members operable in the liner. Another object is to provide a cylinder assembly for an opposed-piston barrel engine with a welded frame having bores receiving removable cylinder liners, each complete with its own water jacket and each located axially by the injection nozzle or precombustion chamber at the middle of the liner's length, and steadied in the bore of the frame by resilient rings at each end of the liner, which rings serve to pack the water passages connecting the water manifolds of the frame with the water jacket of the liner.

These and other objects of the invention will be more apparent from the following description in connection with the drawings in which

Fig. 1 is a longitudinal section of a cylinder liner;

Fig. 2 is a transverse section on the line 2—2 of Fig. 1;

Fig. 3 is a transverse section on the line 3—3 of Fig. 1;

Fig. 4 is a transverse section on the line 4—4 of Fig. 1;

Fig. 5 is a longitudinal section of the frame showing a cylinder liner in place;

Fig. 6 is a central transverse section on the line 6—6 of Fig. 5; and

Fig. 7 is a transverse section on the line 7—7 of Fig. 5.

As shown in Figs. 1—4, the cylinder liner 10 may be built up of tubes and rings, and made integral by furnace brazing; alternately the liner 10 could be cast in one piece, or built up from a casting with water jacket tubes added. Essentially the cylinder liner 10 comprises inner tube 11 forming the cylinder wall, a central ring 12 having a boss 13 for the injector and longitudinal fins 14 to aid in radiation of heat to the cooling

water, a pair of rings 15 and 16 having intake ports 17 and exhaust ports 18 and having longitudinal water passages 19 extending between the ports and connecting the central water jacket 20 with the end portions 21 of the jacket, and a pair of rings 22 closing the jacket at the ends of liner 10. Outside the rings, outer tube 23 in four lengths forms a closure for the water jacket. End rings 22 are provided with water ports 24 thru which water may enter and leave the liner jacket.

Half of the engine frame 50 is shown in Fig. 5, the other half being similar, providing a structure with a plurality of bores 70 of one diameter from end to end, receiving the cylinder liners 10 centrally, and serving as crosshead guides 51 at both ends of the frame. See also Figs. 6 and 7. Each liner 10 is a free fit in bore 70 in frame 50, and is located axially by precombustion chamber 52 piloted in a hole in frame 50 and threaded into liner 10. An injection nozzle might be used to locate liner 10 instead of the precup. At each end of liner 10, resilient rings 53 or neoprene or similar material separated by a perforated spacer 54 are clamped onto the end of the liner 10 by nut 55, and serve to steady or center liner 10 in frame 50 and to pack the water joint thru which cooling water may flow between water manifold 56 in frame 50 and jackets 21 of liner 10 thru ports 24. Water manifold 56 at one end of frame 50 may serve as the water inlet manifold for all liners 10, and at the other end, as water outlet manifold.

Water in water manifold 56 is closed from ports 17 or 18 by the air or exhaust manifold walls 57, formed integral or welded into frame 50. Plates 59 also form parts of the water manifolds with inner tube 60 which may surround the engine shaft and support the main bearings therefor. Outer wall 61, also tubular, serves to close the water manifolds exteriorly, and to form an outer shell on which to seat the closure for the casing, not shown. End plates 62 connect the several bores 70 and form flanges for connecting the end covers not shown to frame 50.

Having thus described the invention, it is obvious that the objects as stated have been attained. While one embodiment of the invention has been shown and described, it is understood that changes may be made in the construction without departing from the spirit or scope of the invention as expressed in the following claims.

I claim:

1. A frame for an opposed-piston internal

combustion engine comprising a welded structure including a central tube for housing the shaft of said engine, and a plurality of tubes spaced about and parallel to said central tube, each having a tubular bore of one diameter from end to end and serving as crosshead guides for said engine; in combination with a cylinder liner unit including its water jacket, freely fitting each of said tubular bores and serving to bush down the central portion thereof so that the cylinder bore of said engine will be substantially less than that of said crosshead guides, and means for locking said cylinder liner unit centrally in its tubular bore.

2. A frame for an opposed-piston internal combustion engine comprising a welded structure including a central tube for housing the shaft of said engine, a pair of plates forming with said cen-

tral tube a water manifold at and surrounding each end of said central tube, and a plurality of tubes spaced about and parallel to said central tube and passing thru holes in said pairs of plates, 5 each of said tubes having a tubular bore of one diameter from end to end; in combination with a cylinder liner unit including its water jacket, freely fitting each of said tubular bores, a fuel injection member entering each tubular bore and cylinder liner radially in its central plane to lock said liner axially in said tubular bore, and resilient water port packing means at each end of said liner unit to seal the flow of water between said water manifolds in said frame and 10 said liner water jackets while centering said liner unit in said tubular bore.

ARNE FEROY.
